UNITED STATES PATENT OFFICE.

JOHN C. WILSON, OF BOSTON, MASSACHUSETTS, ASSIGNOR TO THE MUNICIPAL SIGNAL COMPANY, OF PORTSMOUTH, NEW HAMPSHIRE.

MUNICIPAL SIGNAL APPARATUS.

SPECIFICATION forming part of Letters Patent No. 411,407, dated September 17, 1889.

Application filed July 13, 1886. Serial No. 207,864. (No model.)

To all whom it may concern:

Be it known that I, JOHN C. WILSON, of Boston, county of Suffolk, and State of Massachusetts, have invented an Improvement 5 in Municipal Telegraph Apparatus, of which the following description, in connection with the accompanying drawing, is a specification, like letters on the drawing representing like parts.

- 10 This invention has for its object to simplify the construction of a municipal telegraph system of the class shown and described in Letters Patent of the United States No. 344,467, granted to me June 29, 1886.
- 15 In accordance with this invention, one receiving-instrument is employed at the central station to record the various signals, and an audible alarm is also employed at the central station to indicate whether the signals 20 being received are important signals demanding immediate attention, or patrol-signals, not requiring such attention. The multiple transmitters at the sub-stations are constructed and arranged to transmit the different 25 kinds of signals by changes of different duration in the condition of the circuit, the operation of the transmitters being effected substantially as in the patent referred to. At the central station two relays are placed, 30 constructed and arranged, substantially as will be described, to respond to the changes of different duration in the condition of the circuit, to thereby effect the operation of the recording-instrument, or both the recording- 35 instrument and the audible alarm, according to the character of the signal being transmitted. The central station is also provided with a pole-changer and a signal-transmitting apparatus set in operation from the distant 40 station, to thereby cause an audible alarm to be sounded, or a visual signal to be brought to view at the said distant station to give notice to the officer at the box that something is wanted, a suitable switch under the 45 control of the attendant at the central office being employed to determine whether or not the said signal-transmitting apparatus at the central office shall transmit its signal.

The drawing shows in diagram the instruments at the main and sub stations, and a suit-

able arrangement of circuits to carry out the invention, herein to be described.

The sub-station A is provided with a multiple signal-transmitter consisting of a series of break-wheels a , mounted upon a shaft a' , and rotated one revolution at a time by any suitable motor. (Not shown.) A series of pens a^2 , secured to a frame or bar a^3 , are arranged to be brought in contact with the break-wheels a , one at a time, by the lugs or projections a^5 of a selecting-cylinder a^4 , a pointer p^2 being secured to the end of the selecting-cylinder a^4 and moving over a suitable dial upon the face-plate of the box A, to thereby determine which pen a^2 shall be brought in contact with its respective break-wheel a , such multiple signal-transmitter being substantially such as shown and described in United States Patent No. 331,356, granted to me. The break-wheels a of the multiple signal-transmitter are notched to transmit the different signals desired, some of which—as, for instance, the important signals—being transmitted by breaks or changes of short duration in the condition of the circuit, followed by or preceded by a change of long duration, while others—as, for instance, the patrol-signals—being transmitted by breaks or changes of short duration only, this result being effected by the notches of different length cut in the periphery of the break-wheel. The multiple signal transmitter of each sub-station is included in the main circuit 2 of the battery B at the main or central station. Two relays are included 85 in the main circuit, one of which, as b , is adjusted as in ordinary district telegraphy, that its armature may respond instantly to any change in the condition of the current, and the other, as c , is adjusted with its armature close to or in contact with its cores, in order that the said armature, while being responsive to the changes in the current, lags considerably, so that it will not respond to such changes instantly, or, in fact, not at all 90 to changes of short duration, such as dots, but only upon changes of long duration, such as dashes. By bringing the armature closely in contact with the cores of the relay the residual magnetism exerts a retarding force or re- 100

straining influence upon the armature, this restrained armature being an essential feature of my invention. The armature of the relay *b* controls a local circuit 3, leading from 5 a battery *B'*, said local circuit including a receiving-instrument *d*, herein shown as an ordinary Morse register, and also a releasing-magnet *e*, and a switch *f* is introduced co-operating with the branch wires 4 5 to shunt 10 the releasing-magnet when it is desired that the same shall remain inoperative. The armature of the relay *c*, herein termed for distinction a "lagging" relay, controls a local circuit 5, leading from a battery *B*², the said 15 local circuit including an electro-magnet *g*, the armature of which when attracted releases a drop *h*. The said drop *h*, when released, closes a local circuit 6, leading from a local battery *B*³, said local circuit containing 20 an audible alarm, herein shown as an ordinary vibrating bell *V*.

When the transmitter at the sub-station is operated to transmit a patrol-signal, or a signal requiring no immediate attention, the 25 condition of the current is changed successively for short intervals of time. The armature of the relay *b* responds to such changes, and the receiving-instrument *d* records a series of dots. When the transmitter at 30 the sub-station is operated to transmit an alarm signal, or a signal requiring immediate attention, the condition of the circuit is changed for a long interval of time followed by or preceded by a series of short changes, 35 and in such instance the lagging relay *c* will respond, causing the audible alarm to sound, while the relay *b* also responds in order that the signal may be received by the recording-instrument *d*, it recording a dash, followed by or preceded by a series of dots. 40 Thus it will be seen that upon the reception of an alarm-signal, or one requiring immediate attention, the audible alarm will sound to denote the fact, while upon the reception of 45 any other signal, as a patrol-signal, or one requiring little or no attention, no alarm will be given. As the drop *h* falls, a closed circuit 12, leading from a battery 15, is broken, the said circuit containing an electro-magnet 50 *n*, which controls the movements of a pole-changer *P*, also a break-wheel *p*, mounted upon a suitable shaft and operated by a suitable motor, (not shown,) a contact-pen *p'*, for said break-wheel *p*, the drop *h*, and the armature of the electro-magnet *g*. The motor controlling the operation of the break-wheel *p* is released by the armature of the releasing-magnet *e*, located in the main circuit. As the 55 pole-changer *P* is vibrated by the opening 60 and closing of the circuit by the break-wheel *p*, the main battery is reversed and an impulse of opposite polarity passes over the line to the sub-station and operates a suitable polarized signaling-instrument or bell *S*, located 65 at each sub-station, thereby giving notice to the officer at such station that he is wanted, and he immediately communicates with the

main office by telephone to ascertain what is wanted.

The operation of this portion of the apparatus is as follows: Should the officer at the main station desire to call an officer at one of the boxes, he opens a switch *f* to include the releasing-magnet *e* in the main line, and whenever the transmitter at one of the boxes is operated to transmit a patrol-signal the armature of the relay *b* will respond, closing the local circuit 3, and the releasing-magnet *e* will attract its armature, thereby releasing the motor of the break-wheel *p*, and as said break-wheel revolves the circuit 12 will be opened, successively releasing the armature of the magnet *n*, herein shown as a pole-changing lever, which may be of any suitable construction, to thereby cause an impulse of opposite polarity to pass to the main line at the sub-station or box, and thereby cause the polarized bell *S* to respond. Thus it will be seen that as an officer transmits his patrol-signal, if anything is wanted of him, the bell *S* will 90 respond to denote the fact. When no officer is needed, the switch *f* will remain closed. Should the switch *f* be opened to permit a return-signal to be transmitted to the sub-station upon the reception of a patrol-signal, 95 and an alarm-signal should be sent in, the armature of the relay *c* will respond, as well as the relay *b*, and the drop *h* will fall, as previously described, and by breaking the circuit 12 the magnet *n* will not operate, although 100 the releasing-magnet *e* will permit the break-wheel *p* to revolve, and under such circumstances no return-signal will be transmitted. Thus it will be seen that, as herein shown, upon the occurrence of an alarm-signal no 105 return-signal will be automatically transmitted, but only upon patrol-signals, and only then when the switch *f* is opened; but I desire it to be understood that I do not limit myself to such arrangement, as it is obvious 110 that it may be reversed at will.

It is obvious that instead of transmitting the alarm-signal by a series of changes in the current of short duration, followed by or preceded by a change of long duration, the entire signal may be transmitted by changes of 115 long duration.

I do not herein claim "in an electric circuit, the transmitting apparatus constructed and arranged to produce a series of changes of short duration in the condition of the circuit, and a prolonged change combined with a receiving-instrument responsive to such changes in the circuit, and an audible alarm responsive to the prolonged change only, substantially as described;" nor do I claim "in an electric circuit connecting two stations, circuit-controlling devices at the transmitting-station for changing the condition of the current to produce impulses of short and long duration at will, combined with two receivers located at the receiving-station, one of which responds to the impulses of short duration 120 and the other responds to the impulses of long 125 duration." I do not claim "a receiving-station 130 for receiving the signal transmitted by the apparatus described, and circuit-controlling devices at the receiving-station for changing the condition of the current to produce impulses of short and long duration at will, combined with two receivers located at the transmitting-station, one of which responds to the impulses of short duration and the other responds to the impulses of long 135 duration."

duration only, substantially as described," as the same is not of my invention.

I claim—

1. In an electric circuit, a signal-transmitting apparatus constructed and arranged to produce a series of changes in the circuit of long and short duration, and two relays connected in said circuit, the armature of one of which is acted upon by a retarding force, thereby rendering it responsive only to the changes of long duration, and the armature of the other of which is unrestrained and thereby responsive to all changes in the circuit, substantially as described. 65
2. In an electric circuit, a signal-transmitting apparatus constructed and arranged to produce a series of changes in the circuit of long and short duration, and two relays connected in circuit, the armature of one of which is acted upon by a retarding force, thereby rendering it responsive only to changes of long duration, and the armature of the other of which is unrestrained and thereby responsive to all changes in the circuit, a receiving- 70 instrument controlled by that relay having the unrestrained armature and which is responsive to all changes in the condition of the current, and an audible alarm controlled by that relay having the restrained armature, 75 which is responsive only to changes of long duration, substantially as described. 80
3. In an electric circuit, a transmitting apparatus located at a sub-station and constructed and arranged to change the condition 85 of the current for intervals of long and short duration, a relay located at a main station connected in said circuit and responsive only to changes of long duration in the condition of the current, an electro-magnet and drop 90 controlled by it, a local circuit controlled by said drop, and return-signal-transmitting devices included in said local circuit, and another local circuit also controlled by said drop and containing an audible alarm, substantially 95 as described. 100
4. In an electric circuit, a transmitting apparatus located at a sub-station and constructed and arranged to change the condition of the current for intervals of long and short duration, two relays located at a main station and connected with said circuit, one of said relays being responsive to all changes in the condition of the current and the other responsive to changes of long duration only, a 105 releasing-magnet under the control of the relay which is responsive to all changes in the condition of the current, and a return-signal transmitter controlled by it, and an electro-magnet and drop under the control of the relay 110 responsive only to the changes of long duration, the said drop being included in circuit with the return-signal transmitter, an 115

electro-magnet included in circuit with and responsive to the return-signal transmitter, and a pole-changer operated by said electro-magnet to thereby effect the transmission of the return-signal to the sub-station, substantially as described. 120

5. In an electric circuit, a signal-transmitting apparatus located at a sub-station and constructed and arranged to change the condition of the current for intervals of long and short duration, two relays located at the main station and connected with said circuit, one of said relays having its armature acted upon by a retarding force to thereby respond to the changes of long duration only, the other relay having its armature unrestrained to thereby respond to all changes in the circuit, a releasing-magnet under the control of the relay having the unrestrained armature, and a circuit-changing device for sending the return-signal released by the releasing-magnet, substantially as described. 125

6. In an electric circuit, the combination, 130 substantially as described, of a signal-transmitting device at one station constructed and arranged to produce changes in the circuit of long and short duration, with two relays, the armature of one of which has a retarding or restraining force acting upon it, a register, and a return-signal transmitter controlled by the relay whose armature is not retarded or restrained, and an audible alarm and circuit-breaker controlled by the relay whose armature is retarded or restrained, said circuit-breaker, when operated, rendering the circuit containing the return-signal transmitter inoperative. 135

7. In a police-signal system, an electric circuit connecting a main and a sub station, a signal-transmitting apparatus at the sub-station constructed and arranged to produce changes in the condition of the current for intervals of long and short duration, a register located at the main station responsive to all such changes in the condition of the current, and a relay also located at the main station and connected in said circuit, the armature of which is acted upon by a retarding or restraining force, rendering it responsive only to changes of long duration in the condition of the current, and an audible alarm or indicating signal also located at the said main station controlled by said retarded or restrained armature, substantially as described. 140

In testimony whereof I have signed my name to this specification in the presence of two subscribing witnesses.

JOHN C. WILSON.
